(57) **CLAIM**

The ornamental design for a combination toothbrush, floss dispenser, and tongue scraper, as shown and described.

DESCRIPTION

FIG. 1 is a perspective view of a combination toothbrush, floss dispenser, and tongue scraper showing my new design, with a section of handle shown in an open position;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof, with the section of the handle shown in the closed position;

FIG. 9 is a front elevation view of the design as shown in FIG. 8;

FIG. 10 is a rear elevation view of the design as shown in FIG. 8;

FIG. 11 is a left side elevation view of the design as shown in FIG. 8;

FIG. 12 is a right side elevation view of the design as shown in FIG. 8;

FIG. 13 is a top plan view of the design as shown in FIG. 8; and,

FIG. 14 is a bottom plan view of the design as shown in FIG. 8.
